(57) **CLAIM**

The ornamental design for a vehicle speaker, as shown and described.

DESCRIPTION

FIG. 1 is a front view showing an embodiment of the vehicle speaker;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a perspective view thereof;

FIG. 8 is a perspective view of the design in use; and,

FIG. 9 is another perspective view of the design in use.

FIG. 8 is a perspective view of the vehicle speaker in which a card in broken lines is placed above the design article and a wire in broken lines is connected to the design article. FIG. 9 is a perspective view of the vehicle speaker in which a card in broken lines is placed on top of the design article and a wire in broken lines is connected to the design article.

The broken lines in FIGS. 1-9 illustrate portions of the vehicle speaker that are not part of the claimed design. Any shading and cross-hatching are not features of the design but are utilized to illustrate the surface contours of the vehicle speaker in the drawings.
